United States Patent [19]

Nagase

[11] Patent Number: Des. 427,162
[45] Date of Patent: ** Jun. 27, 2000

[54] ARITHMETIC OPERATION CONTROL
MACHINE FOR AN ELECTRONIC
COMPUTER

[75] Inventor: Koji Nagase, Hachioji, Japan

[73] Assignee: Kabushiki Kaisha Toshiba, Kawasaki,
Japan

[**] Term: 14 Years

[21] Appl. No.: 29/107,801

[22] Filed: Jul. 15, 1999

[30] Foreign Application Priority Data

Jan. 21, 1999 [JP] Japan 11-1249

[57] CLAIM

The ornamental design for an arithmetic operation control
machine for an electronic computer, as shown and described.

DESCRIPTION

FIG. 1 is a front, top and left side perspective view of an
arithmetic operation control machine for an electronic computer,
showing my new design;

FIG. 2 is a front elevational view thereof;

FIG. 3 is a right side elevational view thereof the opposite
side being a mirror image thereof;

FIG. 4 is a top plan view thereof;

FIG. 5 is a bottom plan view thereof; and,

FIG. 6 is a rear elevational view thereof.
